UNITED STATES PATENT OFFICE

2,385,082

VISIBLE INDEX OR RECORD STRIP

Harry J. Hopkins, Chicago, Ill., assignor to Acme
Visible Records, Inc., Chicago, Ill., a corpora-
tion of Illinois

Original application October 27, 1941, Serial No.
416,652, now Patent No. 2,327,525, dated August
24, 1943. Divided and this application July 24,
1942, Serial No. 452,245

3 Claims. (Cl. 154—43)

This application is a division of my copending application Serial No. 416,652, filed October 27, 1941 now Patent No. 2,327,525, dated August 24, 1943.

This invention relates to improvements in visible index or record strips and refers specifically to strips of the class described which carry lines adjacent or at their longitudinal marginal edges distinctively colored from the faces of the strips.

In the use of visible indices or records, such, for example, as described in the issued patent to Frank D. Powell, Patent No. 1,594,112, issued July 27, 1926, difficulty is sometimes encountered in conveniently associating indicia which appear adjacent one end of a strip with the correlated indicia which appear adjacent the opposite end of the strip. When in use, the strips are positioned close to each other upon a suitable frame, such as described in the Powell patent hereinbefore identified, and in view of this fact the lines of demarcation between adjacent strips are not striking and, without the use of an assisting straight-edge, the eye of the operator has difficulty in traversing the length of a predetermined strip to associate indicia adjacent one end of the strip with the correlated indicia adjacent the opposite end.

As a result, errors are likely to occur by the inadvertent raising or lowering of the operator's eye, and the indicia at one end of a predetermined strip may be improperly associated with indicia at the opposite ends of adjacent strips.

My present invention contemplates the provision of index strips of the class described having lines at or adjacent the longitudinal marginal edges of each strip of a color distinct from the color of the face of the strip whereby a guide is provided for the eye of the operator in scanning the length of a strip.

Other objects and advantages of my invention will be apparent from the accompanying drawings and following detailed description.

In the drawings:

Fig. 1 is a transverse sectional view of a suitable machine for carrying out my invention.

Fig. 2 is an elevational view, parts being broken away and parts being shown in section, of the machine illustrated in Fig. 1.

Fig. 3 is a fragmentary view similar to that shown in Fig. 2 of a modification of the machine.

Fig. 4 is a face view of a plurality of strips having marginal lines in accordance with my invention.

Fig. 5 is a similar view of the strips shown in Fig. 4 without such marginal guide lines.

Fig. 6 is an enlarged, lateral edge view of the sheet material illustrated in Fig. 4.

Fig. 7 is a still more enlarged fragmentary lateral edge view of the sheet material of Fig. 6, further illustrating diagrammatically the partial severing of the sheet material into strip form, and the deposition of ink at the time of cutting.

Fig. 8 is a lateral end view of a single severed strip; and

Fig. 9 is a perspective view of a single severed strip.

Referring in detail to the drawings, 1 indicates a machine for cutting strips such as those described in the Powell patent hereinbefore identified. The machine 1 comprises a pair of spaced frames 2—2 which carry a platform 3 at their upper edges. A structure comprising spaced frame members 4—4 is mounted upon the platform 3. A shaft 5 is journaled adjacent its opposite ends in the frame members 2, said shaft carrying intermediate the frame members a bed roll 6 which is keyed to the shaft as indicated at 7 in Fig. 1. A shaft 8 is journaled in the opposite frame members 4 and carries a roll 9 which is keyed to the shaft 8 by means of key 10.

The machine 1 is described only with regard to its essentials. A machine for cutting the indexed strips hereinbefore described is fully set forth in the patent to Frank D. Powell Patent No. 1,804,642 issued May 12, 1931.

Of course it is to be understood that the machine described in Powell Patent No. 1,804,642 may be employed or any suitable strip cutting machine can be utilized in carrying out my present invention.

The roll 9 carries a plurality of axially spaced, circumferential knives 11, and in employing the machine to cut index strips, the periphery of the bed roll 6 is preferably disposed substantially flush with the platform 3. In cutting the strips, a sheet 12 from which the strips may be cut is passed between the rolls 6 and 9, and the knives 11 function to properly cut the sheet into strips of appropriate width.

As fully described in the Powell Patent No. 1,594,112, the visible index strips are formed from a sheet of relatively thin wood veneer. A sheet 50 of paper is adhesively united to each face of the wood veneer sheet and in passing the sheet, indicated as sheet 12, between rolls 6 and 9, the rolls are so adjusted with respect to each other that the knives 11 cut the upper paper sheet and also 55 the sheet of wood veneer but leave the lower paper

sheet intact whereby the sheet of strips may be inserted in a typewriter, for instance, in sheet form, and indicia such as shown at 13 and 14 in Fig. 5 may be inscribed upon the faces of the individual strips. Subsequently, the strips are separated and inserted in the manner described in Powell Patent No. 1,594,112 in a suitable frame.

Fig. 5 indicates the position of a plurality of such strips when held by a frame (not shown). It will be noted that the longitudinal edges of adjacent strips are disposed very close to each other and that a comparatively faint line of demarcation exists between the strips. An operator attempting to utilize such a visible index system may, for example, wish to ascertain the credit rating of "Richard Roe." The eye of the operator in traversing the length of the strip dedicated to "Richard Roe," may raise or lower during the operation and may inadvertently associate the rating "AAA" belonging to "John Doe," with "Richard Roe," or there is the danger of the operator's eye lowering to the strip dedicated to "Frank Smith" and ascribing the rating "DD" to "Richard Roe." It can readily be appreciated that when a large number of these indicia are presented to the eye of the operator, such errors are very likely to occur.

This possibility of error is attributable primarily to the fact that heretofore no striking line of demarcation has been provided between adjacent strips since the strips are usually all of the same base color and the cutting operation tends to form a fillet along the longitudinal edges of the face of the individual strips, which fillet partakes of the color of the face sheet.

In accordance with my invention, I provide a trough 15 which may be mounted by suitable brackets 16 upon the upper edges of the supporting members 4. The trough 15 is adapted to contain wicking 17, or other absorbent material and the lower portion of the trough may be open as indicated at 18 in Fig. 2. The trough 15 is so positioned with respect to the roll 9 that the knives 11 are wiped by the wicking material 17. A quantity of ink or other coloring liquid is deposited in the trough 15 and saturates the wicking 17 whereby a film of coloring material is carried upon the lateral surfaces of the knives 11. In cutting the upper paper sheet and the veneer comprising the sheet 12, the films of coloring material carried upon the knives 11 are transferred to the upper edges of the scored strips. In this manner the dual operation is performed of cutting the strips and simultaneously coloring those portions of the strips adjacent their longitudinal edges.

A plurality of such strips, after the sheet 12 has been properly inscribed and the strips broken, appears in the frame (not shown) as indicated in Fig. 4. It will be noted that in correlating the indicia 13' with the respective indicia 14', the eye is assisted by the colored lines of demarcation 19 and the possibility of error is accordingly reduced.

If desired the trough 15 may carry a plurality of partitions 20 as shown in Fig. 3 and absorbent material such as cotton wicking 21, 22 and 23 may be inserted in the spaces provided between adjacent partitions 20. It will be noted that the knives 11 are each brought into contact with a separate mass of wicking. For instance, the first knife 11 may be wiped by the wicking 21, the second knife by the wicking 22, and the third knife by the wicking 23 and so on throughout the length of the roll.

If desired, the wicking contained in each of the separate compartments may be impregnated or saturated with a distinctive coloring material. For instance, the wicking 21 may be saturated with a red pigment; the wicking 22 with a blue pigment. The wicking 23 may be pigmented red and alternate wickings may be red and blue. Obviously by the provision of separate compartments for the wicking which wipe the individual knives, any desired arrangement of colors can be obtained and, hence, these distinctive colors may be transferred to the longitudinal edges of the strips.

Referring to the enlarged detailed views of Figs. 6 to 9 the sheet material 12 may be composed of an intermediate layer 24 of wood, an upper face layer of paper 25, and a lower backing layer of paper 26. Due to the relative softness of the paper in layer 25 with respect to wood layer 24, the cutting operation illustrated in Figs. 1 and 2 tends to form a fillet along the longitudinal edges of the faces of the individual strips, as previously described. The ink wiped from a rotary knife 11 is deposited essentially along this fillet to produce a line 19, which line while being essentially formed on the longitudinal defining edges of the strips, is also caused to be produced adjacent thereto on the face of the strip or rather on the fillet-like formation, or to lie at a point where the facing of the strip converges to the longitudinal edges of the strip, that is, on the resulting inclined edge or blunt, substantially arcuate corners of the strips.

It is to be understood, of course, that the strips 35 may be cut by devices which operate differently from that shown and described. My invention broadly contemplates, however, the idea of wiping cutting knives for the strips with a coloring material so that a film thereof may be imparted to the longitudinal edges of the strips during the cutting operation.

While I have described and illustrated the concept of my invention as applied specifically to the index strip shown in Patent No. 1,594,112, it is to be understood that my invention in its broad aspects includes all of the conventional index strips now in general use. It is not intended that the invention is limited in any way to the type of index strips shown in said Patent No. 1,594,112. For example, in one index strip structure now in general use the strips are made of wood veneer faced with paper united to a backing sheet from which the separated strips are peeled or stripped. In another structure in commercial use the strips 55 comprises a core of relatively inexpensive fiber such as chip board faced with a print-receiving surface. These strips are completely severed and are united by means of two parallel adhesive tapes disposed at right angles to the length of the index strips.

I claim as my invention:

1. Separate flexible index strips of the class described, comprising strips of wood of greater width and length than thickness faced with paper, the strip face being in inclined merging relationship at the longitudinal edges thereof with the sides of the strip and being inscribed on said inclined edge portions with a color contrasting with the color of the face of the strip and visible from the face of the strip.

2. Flexible index strips in continuous sheet form, comprising a continuous sheet of flexible fibrous material partially severed transversely of the length of the sheet and in the direction of the

depth thereof, to permit subsequent separation into individual index strips, one face of the partially severed sheet presenting a severed appearance and the opposite face of the sheet exhibiting an unsevered appearance, the corners of the merging severed faces and side edges defining said strips being blunt, said blunt corners being inscribed with a line of color contrasting with the color of the face of said strips and visible from the face of the strips.

10

3. An index strip of greater width and length than thickness having a surface adapted to take print, the longitudinally extending corners of said strip defined by the merging sides and said surface thereof being substantially arcuate, said substantially arcuate corners having colored areas thereon contrasting with the color of said surface and visible from said surface.

HARRY J. HOPKINS.
